COMBINED MERCHANTISE DISPLAY AND DISPENSING STAND

Norman R. Welch, 905 Bailey Park Drive NE.,
Grand Rapids, Mich. 49505

Filed Dec. 19, 1968, Ser. No. 15,068

Term of patent 14 years

Int. Cl. D6—01

U.S. Cl. D80—9

FIG. 1.

FIG. 2.

FIG. 3.

FIG. 1 is a perspective view of a combined merchandise display and dispensing stand embodying my new design; FIG. 2 is a side elevational view thereof; and FIG. 3 is a top plan view thereof.

I claim:

The ornamental design for a combined merchandise display and dispensing stand, substantially as shown.
